UNITED STATES PATENT OFFICE.

PALMER M. CADY, OF SAN FRANCISCO, CALIFORNIA, ASSIGNOR OF ONE-HALF TO CHARLES J. KAIGHIN, OF SAME PLACE.

NECKTIE-HOLDER.

SPECIFICATION forming part of Letters Patent No. 677,951, dated July 9, 1901.

Application filed March 11, 1901. Serial No. 50,581. (No model.)

To all whom it may concern:

Be it known that I, PALMER M. CADY, a citizen of the United States, residing in the city and county of San Francisco, State of California, have invented an Improvement in Necktie-Holders; and I hereby declare the following to be a full, clear, and exact description of the same.

My invention relates to an improved collar-button clasp to be secured to a necktie and by which the latter is held in position upon the wearer.

It consists, essentially, of two connected members, each consisting of a plate having a portion bent outwardly and backwardly and then outwardly and forwardly again, the ends provided with segmental notches adapted to grasp the shank of the collar-button and to inclose the head within the jaws so formed by said bent portions.

It also comprises details more fully to be set forth hereinafter.

Figure 1 shows the holder attached to a "bow-tie." Fig. 2 is a top view of the holder using a spring. Fig. 3 shows a plate before transformed into a holder member. Fig. 4 shows it connected with a string-tie.

A represents a plate of metal or other suitable material stamped preparatory to being bent into the shape of one of the holder members. Notches, as 2, are formed in this plate, and one end is provided with a segmental notch 3, sufficient to fit about the shank of a collar-button. To form one of these members, the notched end portion of the plate, on the line of the notches 2, is first bent over upon the portion 5. This folded part is again bent outward and forward to form the jaw 6. The members, which are both similar in form, are connected by means of a hinge, as 7. The hinge in this instance is shown as a piece of wire secured around the members in the notches 2. Thus by means of the lever portions 5 the jaws are actuated and are so formed with their oppositely-disposed segmental notches 3 to grasp the shank of and inclose the head of a collar-button.

The application of the holder is shown as follows: B represents a tie of the ordinary "bow" variety, having bands b, by which it is secured about the neck. The form of device

shown and described is for use with ties of this character, and the lever portions 5 and 5' of the holder being secured to these bands the simple operation of fastening the tie about the neck causes a contraction of the jaws and a secure grasp of the button by them.

Where the holder is to be used with ties without such neckband, it is necessary to provide other means by which the jaws may be made to retain their grasp of the button. This I accomplish by means of a spring 8, which may be secured to the under side of one of the levers 5' and adapted to press against the other lever, as shown, and in such manner as always to tend to hold the jaws closed.

Sometimes it is not possible or desired to secure the holder permanently to the tie, as in the case of string-ties, &c. Then I use the form of device shown in Fig. 4, said device being separate from the tie. In this form the device is adjusted first on the collar-button, and the lever portions 5 5' are provided with bands or straps 9 of metal or other suitable material, and the ends of the tie are passed through these bands or straps and may be tied in any desired manner. The holder may also be ornamented as desired.

Having thus described my invention, what I claim as new, and desire to secure by Letters Patent, is—

1. A necktie fastener or holder, consisting of two hinged members, each member having a straight portion adapted to be secured to the tie, adjacent portions of these members bent outwardly and backwardly and again outwardly and forwardly to form jaws, the ends of these jaws having oppositely-disposed slots, and means whereby the jaws may be actuated.

2. A necktie-holder consisting of two members, each member having a slot in one end, slots in the sides of said members, the portions of the members having the terminal slots, bent on the line of the lateral slots and at right angles to the plane of the straight portion to form jaws, and means by which the members are hinged together.

3. A necktie - holder, consisting of two hinged members, each of said members comprising a straight or lever portion, a portion

bent at right angles to the plane of said straight portion to form a jaw provided with a notch, notches in the meeting edges of these jaws, a spring secured to the under side of 5 one of said straight portions and adapted to bear against the other member whereby the jaws are normally kept closed.

4. A necktie - holder, consisting of two hinged members each having a lever portion, 10 and each having a second portion bent backwardly and thence outwardly from said lever

portion, and adapted to form a jaw, a spring whereby these jaws are held in a normally closed condition, and transverse straps upon the outer side of said lever portions.

15 In witness whereof I have hereunto set my hand.

PALMER M. CADY.
